UNITED STATES PATENT OFFICE.

WALTER P. WHITTEMORE, OF NORTH ATTLEBOROUGH, MASSACHUSETTS,
ASSIGNOR TO ALEXANDER LEVETT, OF NEW YORK, N. Y.

ROTARY POLISHING DEVICE.

SPECIFICATION forming part of Letters Patent No. 267,735, dated November 21, 1882.

Application filed July 13, 1881. (No model.)

To all whom it may concern:

Be it known that I, WALTER P. WHITTEMORE, of North Attleborough, in the county of Bristol and State of Massachusetts, have invented certain Improvements in Rotary Polishing Devices, of which the following is a specification.

My invention relates to rotary polishing devices, or rag or buffing wheels, composed of chamois, leather, cloth, or other suitable yielding material, and adapted to be secured to an arbor and rotated thereby. Heretofore such devices or wheels have been made of superposed disks or sheets of material, each disk having the same area as the device or wheel, and as a large number of disks are required for a single wheel it follows that much expense and waste are involved in the production of the disk.

My invention has for its object to enable a wheel or device of this class to be made from small waste scraps or fragments of material, thereby effecting a considerable saving in expense and utilizing material that would otherwise be wasted.

To this end my invention consists in the improved rotary polishing device or rag-wheel, which I will now proceed to describe and claim.

Of the accompanying drawings, forming a part of this specification, Figure 1 represents a side elevation of one form of the polishing device or rag-wheel embodying my invention. Fig. 2 is a side elevation of the same without the outer disk and washer shown in Fig. 1. Fig. 3 represents a section on the line *x* *x*, Fig. 1. Fig. 4 represents a section on the line *y* *y*, Fig. 2.

The same letters refer to the same parts in all the figures.

In carrying out my invention I take waste scraps or fragments, *b*, of chamois, leather, felt, or other suitable yielding material of small size, the shape being immaterial. These scraps I superpose to form a pile of any desired thickness, the scraps being arranged to radiate or diverge from a common central area, as shown in Fig. 2. In arranging the scraps care should be taken to make the pile as nearly as possible of uniform thickness; but in order to enable the scraps to be secured together at their

inner ends they may have to be overlapped more than at the outer ends, so that the pile may be somewhat thicker at the central portion than at its margin. I connect the scraps firmly together at the central portion of the pile by any suitable means, preferably by means of glue or cement, the inner ends of the scraps being saturated or coated with such material, and then subjected to a very strong pressure until the coated portions are compressed sufficiently to reduce the extra thickness at the center of the pile, caused by the overlapping inner ends of the scraps, the central part of the pile being made, if desired, thinner than the surrounding portions, as shown in Figs. 3 and 4. When the glue or cement hardens the central portion of the pile becomes in effect a rigid homogeneous mass, leaving the outer ends of the scraps free. A central perforation, *d*, is made in the pile to receive an arbor, either by arranging the scraps around a mandrel in forming the pile or by punching or boring the pile after the scraps are united. The pile is trimmed to a circular form after the scraps are united. I prefer to place single disks or pieces *a* upon opposite sides of the pile, said pieces being of the same area as the pile, and keeping the outer scraps, *b*, from lateral displacement. A similar disk or piece may also be placed in the center of the pile, if desired. I also prefer to place collars or washers *c* *c*, of stiff pasteboard or other comparatively-rigid material, upon the outer side of the pile, said collars, as well as the disks *a* *a*, having perforations to coincide with the orifice *d*, and being united to the pile by glue or other means used for securing the scraps together.

I do not limit myself to the employment of either the disks or collars, as either may be omitted; nor do I limit myself to the use of glue or cement as means of securing the scraps together. If desired, the scraps may be connected by stitches passed through and through the pile a sufficient number of times. I prefer the glue or cement, because it unites the scraps most securely, dampens the scraps, and thus enables them to be compressed to a greater degree than they could be if dry, and it retains the pile in its compressed condition when it (the glue or cement) hardens.

I am aware that a buffing-wheel composed of several superposed single disks of yielding material has been hardened at its center by cement. Hence I do not claim a wheel or polishing device made of pieces of yielding material treated with cement at its center, except when said wheel is made wholly or in part of scraps overlapped at the center of the wheel, united by glue or cement, and compressed, as above described. The device thus constructed is intended to be secured to an arbor by a screw-nut, the arbor being inserted in the orifice *d*. It is adapted for polishing or rubbing metal, bone, horn, wood, or other materials, and may be unconfined at the margin when in operation, so that articles to be polished may be inserted between the scraps, or it may be tightly clamped from its center to its margin between collars on the arbor.

20 I have above described the best mode known to me of connecting together and forming into a wheel waste scraps or fragments of flexible material, but it will be understood that I do not limit myself to the precise mode of construction shown.

25 What I claim as new, and desire to secure by Letters Patent, is—

1. An improved rotary polishing device having a central arbor-receiving orifice, and having the polishing-surface composed of superposed scraps or fragments of chamois, leather, felt, or other suitable yielding fabric, substantially as described.

2. The improved rotary polishing device composed of layers of yielding or flexible material, such layers being formed of scraps or fragments of such material, the whole being united together and adapted to receive a central arbor, substantially as specified.

3. The improved rotary polishing device consisting of a pile of superposed scraps or fragments of waste yielding material connected together centrally, provided with a central arbor-receiving orifice and with external disks or single pieces of like material covering the opposite sides of the pile and perforated to coincide with the orifice of the latter, as set forth.

In testimony whereof I have signed my name to this specification in the presence of two subscribing witnesses.

WALTER P. WHITTEMORE.
